CLAIM

I claim the ornamental design for a wallet, as shown and described.

DESCRIPTION

FIG. 1 is a front view of the wallet showing one embodiment of my new design;

FIG. 2 is a rear view of the wallet of my new design;

FIG. 3 is a perspective view of the outer side of the wallet of my new design shown in an open position;

FIG. 4 is a perspective view of the inner side of the wallet of my new design shown in an open position;

FIG. 5 is a front view of the wallet showing another embodiment of my new design;

FIG. 6 is a rear view of the wallet of my new design as shown in FIG. 5;

FIG. 7 is a perspective view of the outer side of the wallet of my new design as shown in FIG. 5 in an open position; and,

FIG. 8 is a perspective view of the inner side of the wallet of my new design as shown in FIG. 5 in an open position.

1 Claim, 2 Drawing Sheets
